Filed Mar. 29, 1965, Ser. No. 84,471

Term of patent 14 years

(Cl. D26—14)

FIG. 1

FIG. 2

FIG. 3

FIG. 4

FIG. 1 is a front perspective view of a telephone, showing my new design;

FIG. 2 is a side perspective view, with the handset omitted for convenience in illustration;

FIG. 3 is a rear elevational view, with the handset omitted for convenience in illustration.

FIG. 4 is a top plan view thereof, with the handset omitted for convenience in illustration.

The dominant features of my new design are shown in solid lines in the drawing.

The characteristic features of my design reside in the dialing recesses being diagonally disposed upon the dialing plate, a portion of the surface of said plate being visible through a square aperture positioned closely adjacent to the top edge of the front of the telephone.

I claim:

The ornamental design for a telephone, as shown and described.
